(57) **CLAIM**

The ornamental design for a teething device, as shown and described.

DESCRIPTION

FIG. 1 is a front, top perspective view of a teething device according to an exemplary embodiment of the present disclosure;

FIG. 2 is a front view of the teething device of FIG. 1;

FIG. 3 is a rear view of the teething device of FIG. 1;

FIG. 4 is a side view of the teething device of FIG. 1, the opposite side being identical thereto;

FIG. 5 is a top view of the teething device of FIG. 1; and,

FIG. 6 is a bottom view of the teething device of FIG. 1.

The broken lines in the drawings illustrate portions of the teething device and form no part of the claimed design.
